UNITED STATES PATENT OFFICE.

JOSEPH W. BETTENDORF, OF BETTENDORF, IOWA.

JOURNAL-BOX LID.

Application filed March 23, 1927. Serial No. 177,655.

This invention relates to journal boxes, and more particularly to lids therefor.

An object of this invention is to provide a journal box lid of the type having an integral pintle pin to cooperate with standard journal box hinge lugs and to provide such a lid with a spring mechanism to apply yielding pressure against the outer face of the lid at substantially the center of the lid, in order 10 to insure a good bearing engagement between the lid and journal box entirely around the four sides of the lid.

Another object of my invention is to provide a rigid cover structure, or journal box 15 lid, wherein a lid body portion, pintle, and connecting straps are associated together as a unit.

Another object of the invention is to provide for relative movement between the integral pintle of the lid and the hinge lug so that the upper marginal portion of the lid will be free to move transversely of the hinge lug.

Another object of this invention is to provide a removable journal box lid having an integral pintle with a spring which bears on the hinge lug and the outer surface of the lid and to a member carried by the hinge lug, causing the spring to exert pressure on 30 the lid.

These and other objects will be apparent from the following description and annexed drawings, in which

Figure 1 is a front elevation of a journal box with the lid in closed position.

Fig. 2 is a side elevation of Fig. 1.

Fig. 3 is a vertical section on line 3—3 of Fig. 1.

Fig. 4 is a vertical section on line 4—4 of 40 Fig. 2.

Fig. 5 is a fragmentary side elevation of the lid in semi-open position.

Fig. 6 is a front elevation of the hood to engage the spring.

Fig. 7 is a side elevation of the hood in 45 Fig. 6.

Fig. 8 is a side elevation of the journal box lid in full open position.

Fig. 9 is a side elevation of the journal box with the lid in closed position showing the hood in two positions.

The journal box 1 is of conventional construction, and is provided with a hinge lug 2 having an eye portion 3 to receive the integral pintle 4 of the journal box lid 5. The lug is provided with suitable flattened por-

tions 6 and 7 which are adapted to be engaged by one portion of the spring as will be more fully described.

The journal box lid 5 has the usual side flanges 8 to fit over the edges 1^a of the journal box and is provided with the integral pintle member 4 adjacent the upper marginal portion of the lid. The integral pintle member 4 is preferably offset from the body portion of the lid and is preferably formed by rolling a cylindrical portion of the metal forming the lid and bending back the wings 9 to overlie the offset connecting straps 10 which connect the pintle with the body of the lid. The wings 9 and connecting straps 10 together constitute a rigid connection between the pintle and the body portion of the lid and are preferably offset from the body portion in order that they may properly fit the standard hinge lug of a standard journal box. The body portion of the lid and straps 10 and pintle member 4 are thus associated together and function as a unit.

The spring member 11 has inturned end portions 11^a which are retained on the outer surface of the journal box lid and substantially at the center thereof by means of the retaining plate 12 which is secured by any suitable means to the lid. The intermediate portions 13 of the spring extend upwardly and are coiled to form the helical spring members 14 between which the intermediate loop portion 15 extends upwardly and carries the roller 16 which bears on the flattened portions 6, 7 of the hinge lug when the lid is in closed or semi-open position.

In order to apply pressure to the spring, so that the lid will be firmly held in tight engagement with the sides 1^a of the journal box opening, a hood member 19 is mounted for pivotal movement on the hinge lug 2. The ends of the hinge lug are preferably cut away to form reduced cylindrical end portions 17 around which loop portions 18 of the hood member 19 are mounted for rotatable movement therewith.

The hood itself is provided with a cylindrical cavity adapted to receive the helical coils 14 of the spring and the hood is also provided with an outwardly extending curved flange 20. When the hood is swung down in the dotted line position shown in Fig. 9, the flange 20 engages the coils 14 and presses them inwardly toward the lid, thus placing pressure upon the roller 16 and the end 11^a of the spring. Upon continued movement

of the hood downwardly the flange 20 slides over the coils of the spring and permits the spring to return outwardly a slight distance to be received within the cylindrical portion 6 of the hood. The spring 11, however, is in depressed condition and the pressure is maintained on the inturned ends 11^a of the spring and the roller 16 carried by the spring.

It will be seen that the hood is maintained 10 against accidental displacement due to the fact that it is necessary, in order to disengage the hood from the spring, to raise the outturned flange 20 and depress the helical coils of the spring a slight amount before 15 the hood can swing upwardly free from the spring.

The body of the journal box lid may be stiffened by suitable depressions 22 as is well understood, and the finger piece 23 may be 20 provided for readily opening and closing the lid against the pressure of the spring.

When the hood member 19 is in spring engaging position so as to cause the portions 11^a of the spring to bear with pressure on 25 the lid and to cause the roller 16 to bear upon the journal box lug, the lid may be opened to semi-open position as shown in Fig. 5 so that the roller bears on the surface 7 of the hinge lug, or the lid may be opened 30 to the full open position shown in Fig. 8.

It will be noted that the eye portion 3 of the hinge lug is of sufficient size to permit movement of the integral pintle of the lid transversely of the eye so that the upper 35 portion of the lid is free to seat itself tightly against the sides or edges 1^a of the journal box.

The terminal loop portions of the hood member extend only part way around the 40 reduced end portions 17 of the hinge lug so that the hood may be removed from the hinge lug by upward swinging movement thereof past the position shown in Fig. 9.

When the journal box lid is in the vertical 45 position shown in Fig. 8 the lid may be moved laterally of the journal box so that the connecting straps and reinforcing wings 9 may pass through the slot 21 of the hinge lug. Thus the lid may be applied to or removed from the journal box and the hood member 19 may be applied to or removed from the hinge lug after the lid has been mounted on the journal box.

It will furthermore be noted that I have 55 provided an advantageous unitary cover structure for a journal box, in which a lid body portion and pintle and connecting straps are associated together and operate as a unit.

60 It will thus be seen that with this construction I have provided a simple and efficient journal box lid which is provided with an integral pintle and which may be readily applied to or removed from a standard journal box hinge lug.

It will also be seen that with my construction, wherein movement of the lid transversely of the hinge lug is permitted under pressure of the spring, the seating of the lid tightly against the four sides 1^a of the 70 journal box is insured.

It will also be seen that I have provided a journal box lid which is rigid in construction and which does away with any danger of losing loose hinge pintles, cotter pins, and 75 the like and which lid, together with the pintle, may be readily formed from a single plate of metal.

Furthermore, it is to be understood that the particular forms of apparatus shown 80 and described, and the particular procedure set forth, are presented for purposes of explanation and illustration and that various modifications of said apparatus and procedure can be made without departing from my 85 invention as defined in the appended claims.

What I claim is:

1. The combination with a journal box provided with a hinge lug, of a rigid unitary cover structure having a lid body portion 90 and a pintle, said cover structure being pivotally connected to the lug by said pintle, a spring member having an end portion engaging the outer face of the lid substantially at the center thereof and the other end portion adapted to cooperate with the hinge lug, a spring compressing member rotatably mounted upon the hinge lug for engaging intermediate portions of the spring to cause the spring to exert pressure upon the outer 100 face of the lid and the hinge lug, whereby the lid is pressed tightly against the journal box.

2. The combination with a journal box having a hinge lug provided with an eye, of a 105 journal box lid having an integral pintle adapted to be inserted within the eye of the lug, a spring member having one end portion engaging the outer face of the lid substantially at the center and the other end portion provided with a roller to bear against the hinge lug, said spring having coiled portions intermediate its ends, a hood member rotatably mounted on the hinge lug and adapted to receive said coiled portions and 110 exert pressure through the spring upon the hinge lug and the outer face of the journal box lid.

3. The combination with a journal box having a hinge lug provided with an eye, of 120 a journal box lid having an integral pintle adapted to be received within the eye of the hinge lug, said pintle being of less diameter than the eye of the lug in order to permit the pintle to move bodily transversely of the lug, a spring member cooperatively arranged with respect to the outer face of the lid and the hinge lug and having an intermediate portion spaced from the lid, means rotatably mounted upon the hinge lug to en- 125 130

- gage the intermediate portion of the spring member and cause pressure to be exerted through the spring upon the surface of the lid and the lug whereby the lid will be 5 tightly seated against the edges of the journal box opening, and whereby the lid will be held by spring pressure in closed or open position.
4. The combination with a journal box 10 having a hinge lug provided with an eye, of a lid therefor having an integral pintle adapted to be received within the eye of the lug, the eye of said lug being of greater diameter than said pintle whereby the upper 15 portion of the lid may move relative to the journal box opening, a spring member having one end portion engaging the face of the lid and the other end adapted to cooperate with the lug, said spring member having 20 intermediate coiled portions, a hood member rotatably mounted on the hinge lug and adapted to engage the intermediate portions of the spring and to hold the spring under compression to exert pressure on the 25 lid and hinge lug, said hood member having an outwardly extending flange to prevent accidental displacement of the hood when in spring compressing position.
5. The combination of a journal box having a hinge lug, of a rigid unitary cover structure having a lid body portion and a pintle, said lug having an eye portion of larger diameter than said pintle to permit 30 slight movement of the pintle transversely of the lug, said lug being also provided 35 with an outwardly opening slot from the eye portion, a spring cooperatively arranged to exert pressure on the outer face of the lid and said hinge lug, a spring engaging member having curved arms to be 40 rotatably inserted on the end portions of the lug, said member being adapted to engage the intermediate portion of the spring and exert pressure on the lug and lid respectively, said curved arms extending only 45 partially around the lug whereby the spring engaging member may be applied to and removed from the lug when the lid is in place.
6. The combination with a journal box 50 provided with a hinge lug having an eye, of a rigid unitary cover structure having a lid body portion and a pintle adapted to be received within the eye of the hinge lug, said pintle being of less diameter than the eye 55 of the lug in order to permit the pintle to move bodily transversely of the lug, a spring member cooperatively arranged with respect to the outer face of the lid and the hinge lug, and a spring compressing member rotatably mounted on the hinge lug for engaging intermediate portions of the spring 60 to cause the spring to exert pressure on the outer face of the lid and the hinge lug whereby the lid is pressed tightly against the journal box.

65 In testimony whereof I affix my signature.

JOSEPH W. BETTENDORF.
